EXTENSIBLE HACK SAW FRAME

Gustav A. Lindenau, Stevenson, Wash.

Application July 28, 1950, Serial No. 176,398

2 Claims. (Cl. 145—34)

1

This invention relates to hand saws, and more particularly to an extensible hacksaw frame.

An object of this invention is to provide a hacksaw frame which is particularly adapted to receive and tension hacksaw blades.

Another object of this invention is to provide a hacksaw frame which is particularly adapted for quickly and speedily replacing an interchangeable standard hacksaw blade.

A further object of this invention is to provide an extensible hacksaw frame which is readily adjustable for different sizes of hacksaw blades.

A still further object of this invention is to provide an extensible hacksaw frame which is relatively simple in structure and cheap to manufacture.

The above and still further objects and advantages of the invention will become apparent upon consideration of the following detailed description of the invention, when taken in conjunction with the accompanying drawings, wherein:

Figure 1 is a side elevational view of the hacksaw frame of the present invention, shown supporting a hacksaw blade;

Figure 2 is a fragmentary top plan view of the extensible hacksaw frame shown in Figure 1;

Figure 3 is an enlarged fragmentary sectional view taken along the line 3—3 of Figure 1; and

Figure 4 is a fragmentary side elevational view of the extensible hacksaw frame of the present invention, shown in position for adjustment to receive any of a plurality of sizes of standard hacksaw blades.

Referring now more particularly to the drawings, wherein like reference numerals have been used throughout the several views to designate like parts, there is shown the extensible hacksaw frame of the present invention, generally designated by the reference numeral 10 supporting a hacksaw blade 11.

The hacksaw frame 10 embodies a supporting plate 12 which is provided with an arm 13 depending from one end thereof, the plate and arm forming a supporting member. Positioned contiguous to one side of the supporting plate 12 and secured thereto is a handle 14 for manually grasping the frame 10.

Positioned transversely of the supporting plate 12 contiguous to the end remote from the depending arm 13 is an open-end sleeve 15 which has one end fixedly secured to the plate 12. Supported in the sleeve 15 is an L-shaped arm 17 which has its long arm 18 extending into

one end of the sleeve 15 and projecting from the other end thereof. The short leg of the L-shaped arm, designated by the reference numeral 19, is disposed in substantially side-by-side spaced relation with respect to the depending leg 13 of the supporting plate 12 and is movable toward and away from the latter upon movement of the long leg 18 thereof with respect to the sleeve 15.

Secured transversely of the free end of the depending arm 13 and the short leg 19 are the supporting barrels 20 and 21. Each of the barrels is provided with a longitudinally extending bore 22, 23 for the reception of a supporting rod 24, 25. Contiguous to their outer ends, each of the rods 24, 25 has secured thereto an abutment plate 26, 27 for engagement with the adjacent end of the barrel 20, 21. Contiguous to their inner or free ends, the rods 24, 25 have secured thereto transversely extending pins 28, 29 which are engageable within the apertures provided in the ends of the saw blade 11 to thereby support the blade therebetween. Accordingly, upon tensioning the rods 24, 25, the blade 11 will be fixedly secured therebetween.

Operatively connected to the L-shaped arm 17 and the sleeve 15 is a hand actuated means, generally designated by the reference numeral 30 for holding the L-shaped arm 17 in a select position of its movement with respect to the sleeve 15. The hand actuated means 30 embodies a tensioning linkage 31 which overlies the sleeve 15 and has one of its ends pivotally connected to the free end of the long leg 18 of the L-shaped arm 17. As clearly illustrated in

the drawings, the tensioning linkage 31 embodies two bars 32 and 33 disposed in side-by-side spaced relation with respect to each other and having one end connected by means of the U-shaped bracket 34 and the pin 35 to the free end of the long leg 18 of the L-shaped arm 17. The other ends of the bars 32 and 33 are upwardly offset, as indicated by the reference numerals 36 and 37, into spaced, parallel relation with respect to the upper face of the sleeve 15. Circumposed about the sleeve 15 and slidable therealong is a yoke 38 which includes a depending dog 39. With reference to Figure 3, it will be seen that the yoke 38 is of a size such as to permit endwise play relative to the sleeve 15. The adjacent upper face of the sleeve 15 is provided with a plurality of longitudinally spaced notches, generally designated by the reference numeral 40, for selective engagement with the depending dog 39. Positioned contiguous to the

upper end of the yoke 38 is a lever 41 which

has one of its ends pivotally connected to the yoke by means of the pin 42. As clearly illustrated in Figure 2, the upwardly offset ends 36 and 37 of the bars 32 and 33 are arranged on opposite sides of the lever 41 and pivotally connected to the latter intermediate its ends by means of a movable pivot 43. The free end of the lever 41 is provided with a hand grip 44 for effecting the rotary movement of the lever 41 about the pivotal axis 42. Secured to the depending dog 39 of the yoke 38 is a spring 45 which is engageable with the sleeve 15 for normally urging the depending dog 39 into engagement with the notches 40. As clearly illustrated in Figure 4, the spring 45 embodies offset end sections 46 and 47 interconnected by an inclined connecting section 48. The offset end section 47 is disposed contiguous to and beneath the pivotally supported end of the lever 41.

In actual use, the lever 41 is rotated from the position illustrated in Figure 1 in a clockwise direction to the upright position indicated in Figure 4, and then the lower end of the yoke 38 is slid manually toward the bracket 34 or the dotted position shown in Figure 4, resulting in the movement of the dog 39 out of engagement with the notches 40. While the yoke 38 is being manually held in the dotted position shown in Figure 4 with the dog 39 free of engagement with the notches 40 and the lever 41 in its upright position, the sleeve 15 is manually slid back along the long arm 18 toward the short leg 19. At this point, the lower end of the yoke 38 is released, resulting in the dog 39 being shifted into loose engagement with the adjacent one of the notches 40 by means of the spring 45 or the full line position of Figure 4. The lever 41 is then actuated in a counterclockwise direction until the short leg 19 is spaced from the supporting rod 25 to accommodate a saw blade 11 of a length to be inserted therebetween. The saw blade 11 is then disposed intermediate the free ends of the depending arm 13 and the short leg 19 of the L-shaped arm 17 and is engaged by the pins 28 and 29. The hand grip 44 is then grasped and the lever 41 rocked about the pivotal axis 42 to the position indicated in Figure 1. During this rocking movement of the lever 41, the blade 11 is tensioned, and the lower end of the yoke 38 is simultaneously tilted toward the short leg 19 resulting in the lower end portion of the yoke 38 being caused to engage the adjacent portion of the sleeve 15 and the dog being moved into tight bearing engagement with the adjacent one of the notches 14, the position shown in Figures 1 and 3.

To effect release of the L-shaped arm 17 for sliding movement it is merely necessary to grasp the hand grip 44 and rotate the lever 41 to the upright position of Figure 4, detach the blade 11 from engagement with the pins 28 and 29, and then shift the lower end of the yoke 38 to the dotted line position of Figure 4 to thereby move the dog 39 out of engagement with the notches 40.

Although only one embodiment of the extensible hacksaw frame of the present invention has been described, it is readily apparent that numerous modifications can be made without departing from the spirit of the invention as set forth in the appended claims.

What I claim is:

1. A frame for supporting and tensioning a saw blade comprising an upstanding supporting member, an open ended sleeve positioned adj-

cent the upper end of said supporting member and fixedly secured to the latter, an L-shaped arm having its long leg extending slidably through said sleeve, the short leg of said L-shaped arm being disposed in side by side spaced relation with respect to said supporting member, means on the free end of said short leg and the lower end of said supporting member for the support therebetween of a hacksaw blade, and hand actuated means operatively connected to the long leg of said L-shaped arm and said sleeve for holding said L-shaped arm in select positions of its movement relative to said sleeve, said means comprising a linkage positioned longitudinally of said sleeve and having one end pivotally connected to the free end of said long leg of said L-shaped arm, a yoke loosely circumposed about and slidable along said sleeve, a dog carried by the upper end of said yoke and selectively engageable with a plurality of longitudinally spaced notches provided on the adjacent face of said sleeve, and a lever arranged exteriorly of said yoke and having one end connected to the upper end of said yoke for movement about an axis transverse of said sleeve and connected adjacent said one end to the other end of said linkage for movement about another axis transverse of said sleeve.

2. A frame for supporting and tensioning a saw blade comprising an upstanding supporting member, an open ended sleeve positioned adjacent the upper end of said supporting member and fixedly secured to the latter, an L-shaped arm having its long leg extending slidably through said sleeve, the short leg of said L-shaped arm being disposed in side by side spaced relation with respect to said supporting member, means on the free end of said short leg and the lower end of said supporting member for the support therebetween of a hacksaw blade, and hand actuated means operatively connected to the long leg of said L-shaped arm and said sleeve for holding said L-shaped arm in select positions of its movement relative to said sleeve, said means comprising a linkage positioned longitudinally of said sleeve and having one end pivotally connected to the free end of said long leg of said L-shaped arm, a yoke loosely circumposed about and slidable along said sleeve, a dog carried by the upper end of said yoke and selectively engageable with a plurality of longitudinally spaced notches provided on the adjacent face of said sleeve, a spring having one end secured to said dog and having the other end engageable with said sleeve for urging said dog into engagement with said notches, and a lever arranged exteriorly of said yoke and having one end connected to the upper end of said yoke for movement about an axis transverse of said sleeve and connected adjacent said one end to the other end of said linkage for movement about another axis transverse of said sleeve.
